LOCK-UP SET

Charles S. Wilson, Miami, Fla.

Application September 27, 1938, Serial No. 231,975

2 Claims. (Cl. 101—391)

This invention relates to a lock-up set, the primary object of the invention being to provide a lock-up set designed for holding type forms, such as Linotype slugs, cuts or the like at various angular positions with respect to the side members of the printer's chase, in which the lock-up set is positioned.

An important object of the invention is to provide an angular lock-up set, or lock-up furniture constructed in such a way that it may be securely locked in the usual printer's chase, eliminating the necessity of making changes in the chase construction now in common use, to position the lock-up set.

Another important object of the invention is to provide a lock-up set for positioning within a chase, which may be readily and easily operated to adjust the angular position of the slug, cut or printing form held therein, without the necessity of removing the lock-up set or printing form held therein.

With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

Referring to the drawing:

Figure 1 is a plan view of a printer's chase, showing a lock-up set constructed in accordance with the invention, as positioned therein.

Figure 2 is a perspective view of one of the outer sections of the lock-up set.

Figure 3 is a perspective view of one of the inner sections of the lock-up set.

Referring to the drawing in detail, the usual printer's chase is indicated generally by the reference character 5, which chase provides a frame for the blocks 6, forming a part of the lock-up furniture employed in securing the type or printing matter, in position in the frame.

The lock-up furniture also includes inner blocks 7 which are spaced from the blocks 6, by means of the quoins 8 usually employed in lock-up furniture for exerting pressure on the type matter held within the chase.

The lock-up set forming the essence of the present invention, includes an inner frame embodying outer sections 9 and inner sections 10,

the outer sections having right-angled outer surfaces 11 against which the inner blocks of the lock-up set, engages.

The outer sections 9 are formed with inner curved surfaces 12 curved in the arc of a circle, 5 and designed to conform to the curvature of the outer surfaces 13 of the inner sections 10. As shown, the inner sections 10 have right angled inner surfaces 14 so constructed that they will accommodate the right angled surfaces or corners of the slug, cut, or similar type supporting member positioned within the device.

Graduations indicated at 15 are formed on one edge of one of the outer sections 9, the graduations cooperating with indicator 16 carried by 15 the inner sections 9, so that the frame formed by the inner sections of the lock-up set, may be rotated to adjust the slug, cut or type matter, at various angles with respect to the sides of the chase.

It will further be seen that due to this construction, the slug, cut or type matter may be readily removed and accurately replaced, should it be necessary to make corrections in the type matter.

I claim:

1. A holder for holding type forms in predetermined angular positions within a printer's chase, comprising an outer sectional member and an inner sectional member, the inner sectional member being mounted for rotary adjustment within the outer sectional member, said inner sectional member having rectangular surfaces for the reception of a type form, and said outer and inner sectional members having cooperating curved surfaces, and means for securing the holder within a printer's chase.

2. A holder for holding type forms in predetermined angular positions within a printer's chase, comprising a frame, embodying an outer 40 member and an inner member, the outer member embodying a plurality of sections, said inner member comprising a plurality of sections, the outer sections having right angular outer surfaces and curved inner surfaces, the sections of the inner member having curved outer surfaces and rectangular inner surfaces and adapted to fit over the corners of the type form positioned therein, a chase in which the holder is positioned, and means for securing the holder within the 45 chase.

CHARLES S. WILSON.
